DESIGN FOR A DRESS

Irwin Kranz, New York, N. Y.

Application July 31, 1936, Serial No. 64,155

Term of patent 3½ years

To all whom it may concern:

Be it known that I, Irwin Kranz, a citizen of the United States of America, residing in city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view of the dress as shown in Fig. 1.

Fig. 3 is a front view of the blouse.

The blouse back is conventional.

The characteristic feature of my design resides in the one-piece appearance of the yoke and collar portion of the blouse in combination with the guimpe section as shown.

I claim:

The ornamental design for a dress substantially as shown and described.

IRWIN KRANZ.
